CARL W. TILLMANNS, OF BRIDGEPORT, AND CARL SOHN, OF STRATFORD, CONNECTICUT,
ASSIGNORS TO REMINGTON ARMS COMPANY, INC., A CORPORATION OF DELAWARE

METHOD OF MAKING BOLSTER AND SCALE STRUCTURES

Application filed July 28, 1924. Serial No. 728,598.

This invention relates to cutlery and particularly to pocket knives of the type comprising lining or "scale" members which may line a blade containing recess and exteriorly support the handles. It is common practice to attach tips or "bolsters" to each exterior scale adjacent its ends, said bolsters and scale forming a shallow recess adapted to contain a handle of wood, bone, horn, pearl or other suitable substance.

One object of the present invention is to provide an improved method of making a bolster and scale structure.

A further object of the invention is to construct a combination bolster and scale.

A further object of the invention is to provide a new and improved method of joining bolsters and scales.

A further object of the invention is to provide a method of constructing a bolster and scale in which said parts are formed and joined in one operation.

A further object of the invention is to construct a knife embodying a combination bolster and scale made as hereinafter described.

With these and other objects in view our invention consists in the novel processes, combinations and arrangements of parts which are illustrated in the drawings and will be hereinafter described.

In the drawings:

Fig. 1 comprises an assembly view of the pieces from which the combination bolster and scale is formed, and a view of these parts ready for the forming operation.

Fig. 2 shows a plan and an elevation of the untrimmed combination bolster and scale as it comes from the forming press.

Fig. 3 shows a plan and an elevation of the finished and trimmed bolster and scale.

Fig. 4 is an enlarged section on the line 4—4 of Fig. 3.

Fig. 5 is a perspective of a knife embodying my invention.

In the manufacture of pocket knives as practiced hitherto, bolsters and scales have been separately made and subsequently fastened together by riveting or otherwise.

Scales have usually been punched from sheet

material of the desired thickness, trimmed, and perforated to receive a bolster securing rivet. Bolsters have been separately formed from bar stock, and a rivet, sometimes integral with the bolster, served to secure bolster and scale together. In the practice of our invention the three processes of forming the bolster, forming the scale, and securing a bolster cover to the scale are performed simultaneously.

The scale forming stock consists of a length of wire or rod 5, preferably of circular cross section. The wire may be of iron, brass, German silver, or other desired material. The bolster covering parts 6, which may be of any desired material, either the same as or different from the scale material, comprise cups which may be of circular section, adapted to fit loosely over the ends of the scale forming wire 5. While these cups may be prepared in any suitable manner we prefer to punch them from sheet stock in a "cupping press", adapted to strike a circular blank from the sheet and to form said blank into a cup in one operation of the machine.

A cup 6 is placed on each end of the rod or wire 5, and this assembly is placed in a die of suitable configuration, in a punch press, and is formed by a single operation of the press into the combination bolster and scale blank shown in Fig. 2. Preferably the lower member of the die is recessed to the shape of the blank, and the upper member is substantially flat. The rod 5, except the end sections is flattened to form the scale proper. The ends of the rod take the general shape of spherical segments 8 which form a part of the bolster. Segments 8 are covered except at the face 10 adjacent the handle recess, by the material supplied by cups 6; which thus forms a cover 9 over both the ends of the inside of the scale and the outside of the bolster, as clearly shown in the sectional view, Fig. 4. A part of the body of the bolster is thus integral with the scale, while the material forming the outside of the bolster completely surrounds the scale, and is formed on and simultaneously with the scale, thus insuring a firm and permanent connection between them.

The bolster scale is finished to the form 100

shown in Fig. 3 by one or two trimming or "shaving" operations, and is then ready for assembly with the other parts of a knife. A simple knife including a bolster scale embodying our invention is illustrated in Fig. 5.

5 The term "scale" as used in this specification and in the appended claims refers to a flat metallic member, adjacent to the blade containing recess of a pocket knife, and 10 sometimes referred to as a "lining", to which exterior grip members or "handles" are ordinarily secured.

Our invention is not to be considered as limited to the precise construction and method of operation herein described, but is to be construed as covering all equivalent devices and methods falling within the scope of the appended claims.

20 We claim:

20 1. In the manufacture of pocket knives, the method of making a unitary bolster and scale structure which comprises providing an assembly consisting of a suitable length of wire or rod having cups loosely placed on the 25 ends thereof, and forming from said assembly a unitary bolster and scale blank by a single operation of a suitable swaging press.

2. In the manufacture of pocket knives, the method of securing a bolster cover to a scale 30 which comprises providing a scale forming element of relatively great thickness, covering the ends of said scale forming element with a cup shaped bolster cover forming element, and joining said elements while forming them to approximately finished shape by 35 a single operation of a swaging press.

3. In the manufacture of pocket knives, the method of securing a bolster cover to a scale which comprises providing a scale forming 40 element of circular cross section, placing upon the end thereof a bolster cover forming element of circular cross section and simultaneously uniting said elements, and forming the unitary structure to approximately finished 45 shape by a single operation of a swaging press.

4. In the manufacture of pocket knives, the method of making a bolster which comprises providing a cup of bolster covering material 50 and a rod of bolster core forming material, applying said cup to the end of said rod and simultaneously uniting said elements, and forming the resulting structure to approximately finished shape by a single operation of 55 a suitable swaging press.

5. In the manufacture of pocket knives, the method of making a unitary bolster and scale structure, which comprises swaging the scale portion of said structure from a bar and in 60 the same operation swaging the bolster portion of said structure from a cup element positioned over the end of said bar.

6. In the manufacture of pocket knives, the method of making a bolster, which comprises 65 providing a cup of bolster covering material

and a rod of bolster core forming material, applying said cup to the end of said rod, and simultaneously uniting said elements, forming a bolster cover from the cup and deforming the rod into the bolster core in a single 70 swaging operation.
